UNITED STATES PATENT OFFICE.

W. FILKINS, OF LANCASTER, NEW YORK.

CARPET-FASTENER.

Specification of Letters Patent No. 20,341, dated May 25, 1858.

To all whom it may concern:

Be it known that I, WARREN FILKINS, of Lancaster, in the county of Erie and State of New York, have invented certain new and 5 useful Improvements in Carpet-Fasteners; and I do hereby declare that the following is a full, clear, and exact description of the same, reference being had to the accompanying drawings and to the letters of reference marked thereon.

The nature of my invention consists in the combination of a swinging slotted cap with a plate and spur as will be hereinafter fully described.

15 In order that those skilled in the arts may make and use my invention I will proceed to describe its construction and operation.

In the annexed drawing Figure 1 is a perspective view of a portion of the floor and 20 chair board, the fastener being secured to the floor. Figs. 2 and 3 represent side views of the fastener in different positions. Fig. 4 is a view of the cap showing the groove in it.

25 This fastener consists of three parts, the swinging cap (a), the plate (c) and the spur (b). The plate (c) is a semi circular piece of sheet metal provided with holes (i i) for the purpose of securing it to the floor. b, is 30 a spur secured to this plate (c) as seen in the drawing.

(a), is a cap made in the form shown in the several figures, said cap having a small groove on its under side as seen in Figs. 2 and 4, which allows it to slide over the 35 spur. This cap revolves on a pivot which secures it to the plate (c).

(d) represents the floor and (e) the chair board.

In operating this invention, the plates (c) 40 are secured to the floor at such intervals as may be required by means of screws or tacks—the straight side to the chairboard as shown. When the carpet is to be laid down the cap (a) is swung around as seen in Fig. 45 2; the carpet is then pressed down upon the spur, and the cap swung back as in Fig. 3, the spur entering the groove and the carpet secured.

Having thus fully described my invention 50 what I claim as new and desire to secure by Letters Patent is—

The arrangement of the horizontal swinging slotted cap (a) with the plate (c) and the spur (b) in the manner herein specified 55 and for the purpose set forth.

WARREN FILKINS.
